UNITED STATES PATENT OFFICE.

CLARENCE W. FOSTER, OF CHLORIDE, ARIZONA.

DEMOUNTABLE RIM.

1,287,276.

Specification of Letters Patent. Patented Dec. 10, 1918.

Application filed February 9, 1918. Serial No. 216,298.

To all whom it may concern:

Be it known that I, CLARENCE W. FOSTER, a citizen of the United States, residing at Chloride, in the county of Mohave and State 5 of Arizona, have invented new and useful Improvements in Demountable Rims, of which the following is a specification.

This invention relates to wheels, and more especially to those having metallic rims; 10 and the object of the same is to produce a demountable rim for wheels which are employed mostly on motor vehicles.

The invention comprises a rim slipped axially onto the felly or onto a band 15 rounding the same, means for holding it thereon to prevent it from creeping, and a lock consisting of a ring screwed onto the projecting outer edge of said felly or band and having a nut lock to prevent unscrew- 20 ing; and the invention also consists in details employed in carrying out this broad idea.

The following specification sets forth my preferred manner of carrying out this invention, reference being had to the accompanying drawings wherein:

Figure 1 is a perspective view of a portion of the completed structure, partly broken away to show the notch for the entrance of the nipple, the whole structure being in section in the foreground, and the tire being indicated only in dotted lines.

Fig. 2 is a plan view of a portion of the band around the felly.

Fig. 3 is a bottom or inner plan view of a corresponding portion of the rim.

Fig. 4 is a bottom plan view of a portion of the ring, and

Fig. 5 is a side elevation of a fragment 40 thereof, partly broken away.

Fig. 6 is a sectional detail of a portion of the band partly broken away to show the catch.

The spokes S carry the usual felly F, and, 45 while I may apply the rim directly to the outer face of the felly, especially if the latter be of metal, I prefer to surround the felly with a fixed band B of metal herein-after separately referred to as the "band" 50 although it is to be understood that it might be a part of the felly itself. The tire shown in Fig. 1 comprises the usual casing C and

air tube T. No invention is claimed for the parts thus far mentioned.

The band B is preferably a flat and 55 rather wide face, and as shown it might be wider than the outer face of the felly. Of necessity it has an inner outturned flange 1, while around its outer edge it has a thread 2 cut into its outer face. By this I mean 60 to say that it is a thread groove rather than a thread rib, and it does not enlarge the peripheral side of the band—thus leaving it possible to slip the rim over this groove. I might here state that the thread is of very 65 gentle pitch, and extends only once around the complete band; yet it may be a single groove or a plurality of grooves, or in other words a double thread as clearly understood. This thread groove is to be engaged by a 70 thread rib 3 on the inner face of a ring 4 whose section is preferably about the same as that of the flange 1 at the inner edge of the band excepting that at one point it has a knob or handle 5 by means of which it 75 may be turned when it is put in place. It is in effect a large nut screwed onto the thread 2 at the outer edge of the band to hold in place the rim yet to be described, and its thread rib (or ribs) by preference 80 makes only one complete revolution, although it also may be a double rib as the thread 2 is a double groove.

At a proper point a nut lock is provided. By preference I provide the ring with a 85 recess terminating in a hole 8 extending through it, and within said recess is pivotally mounted a rocking catch whose tip 7 is projected through said hole by means of a spring. Opposite the other or rear arm 90 of the rocking catch is a button 6 having a cupped outer end exposed at the outside of the ring, and when any suitable instrument such as a nail or a match is pressed into this cupped end, the button rocks the 95 catch against the tension of its spring and withdraws its tip. At other times the spring projects said tip, so that it engages with one of a number of teeth 9 formed in the edge of the band at a point to come opposite said tip when the ring is screwed into place. This entire device constitutes a nut lock, and it is completely housed and protected from the weather and dust and dirt,

No part of the button projects beyond the exterior contour of the ring, and therefore it can not be accidentally hit. When depressed it throws the nut lock out of action, 5 and permits the unscrewing of the ring.

The demountable rim 10 has a channeled body which is narrower than the width of the band, and at its edges it is preferably provided with flanges 11 and 12 which are 10 inturned to embrace the beads of the casing C as usual. I do not wish to be limited in this respect, however, because the tire might be of the cushion type, it might be fastened rigidly to the outer face of the rim, or it 15 might in fact be of metal or other material or perhaps integral with the rim itself although in such case there would not be the necessity for demounting the rim which usually exists where the tire is of the pneumatic type, and therefore we are considering the invention on this basis. The inner face of the rim is preferably flat, and also by preference its circumference is appreciably larger than that of the outer face of the band so 20 that a space 13 exists between these elements; yet this space does not fill up with mud and dirt because it is closed at the inner edge by the flange 1 and it is closed by the ring 4 at the outer edge when the parts are assembled. I purposely produce this space between these elements in order that the rim may slip easily over the band when it is put on and taken off, and yet in order to prevent creeping I provide the outer face of the 25 band at appropriate points with spaced lugs 14, and the inner face of the rim at corresponding points with other lugs 15, all lugs being transverse to the elements or in other words parallel to the axis, so that when the 30 rim is applied it may slip easily onto the band and each of its lugs 15 will pass between the two corresponding lugs 14 on such band. By preference I use about four sets of these lugs, although I do not wish to be 35 limited thereto. The lugs may be straps of considerable width, and the inner end of the lug 15 on the rim is by preference tapered as at 16 so that it will pass readily between the corresponding lugs 14. 40

At one point in the wheel the felly and rim are notched as at 17 between two of the lugs 14, and at a corresponding point the rim is provided with a hole 18 as shown. When now a pneumatic tire is put onto this 45 rim, the nipple N is passed through said hole and projects radially inward as well understood, and when later the rim with its tire is slipped onto the band, the projecting nipple passes into the notch 17 as the lug 15 50 passes between the lugs 14. If the tire were not of the pneumatic type, or if its tube were inflated by some other means, as by means of a nipple which projected in some other direction, these details of structure would not 55 be necessary; but I describe and illustrate

them in order to adapt the invention to pneumatic tires in the form now in common use.

In the use of this invention, let us assume that the parts are assembled as seen in Fig. 70 1. When now the operator desires to remove the rim and its tire, he trips the catch or nut-lock, whatever its form, grasps the knob or handle 5 on the ring 4, and turns the latter in a direction to unscrew it off the 75 outer edge of the band B. As above suggested, a single thread only, or a single convolution of the thread only is employed, and therefore only a single revolution of the ring is necessary to unscrew and remove it. The 80 rim 10 and tire may now immediately be slipped off the wheel from the outside, and this is more readily accomplished because of the fact that the rim and band are connected only at about four points where the interengaging lugs 14 and 15 exist, and practically no mud and dirt has been permitted to accumulate at other points between these elements. If the user has not another rim and inflated tire ready for application, he then 85 removes the deflated and perhaps defective tire from the rim, and repairs and replaces it in a manner not necessary to amplify. For this purpose the flanges 11 and 12 may be suitably formed to engage the beads at 90 the edges of the casing, but this detail forms no part of the present invention. In either case, however, when he comes to replace the rim and its tire, he has but to slip it back onto the band from the outer side of the 100 wheel, taking care that the nipple N passes into the notch 17. Pressing it onto the band until its inner flange 11 contacts with the inner flange 1 on the band, he now brings the ring 4 into position, engages its thread 105 3 with the thread 2 on the outer edge of the band B, grasps its knob or handle 5, and gives it a turn. One turn will be ample to screw it tight against the outer flange 12 of the rim, and just at this time the teeth 9 110 come over the tip of the catch 7 and the latter is projected through the hole 8 to lock the ring against a retrograde movement. If the tire T is not already inflated, a pump is 115 now attached to the nipple N and manipulated to supply the required amount of air, and all is well. The application of the ring 4 closes the outer edge of the space 13 between the rim and the band, and therefore as the motorist proceeds on his way practically no dust or mud can get into this space between such elements—yet there are sufficient points of contact between the interengaging lugs 14 and 15 around the circumference of the wheel to prevent distortion or 120 bending of the rim 10 under the weight of the load. The parts are of the desired sizes, shapes, proportions and materials, and details other than as hereinbefore given are not 125 essential.

What is claimed as new is:—

In a demountable rim, the combination with a felly, and a band around the same having an outturned flange at its inner edge 5 and a thread groove around its outer edge and teeth in said edge at one point; of a ring having a thread rib on its inner face adapted to engage said groove, a rim surrounding said band and of a width to be

clamped between its flange and the ring 10 when the latter is in place; a catch on the ring coming opposite said teeth when such ring is in place, interengaging elements on the contiguous faces of the rim and band for preventing creeping of the rim, and 15 means on the latter for carrying a tire.

In testimony whereof I affix my signature.

CLARENCE W. FOSTER.
